UNITED STATES PATENT OFFICE.

ANTHONY FRICKER, OF PITTSBURG, PENNSYLVANIA.

GAS AND GASOLENE ENGINE.

No. 894,622.

Specification of Letters Patent.

Patented July 28, 1908.

Application filed October 24, 1906. Serial No. 340,355.

To all whom it may concern:

Be it known that I, ANTHONY FRICKER, a citizen of the United States of America, residing at Pittsburg, in the county of Allegheny and State of Pennsylvania, have invented certain new and useful Improvements in Gas and Gasolene Engines, of which the following is a specification, reference being had therein to the accompanying drawing.

10 This invention relates to gas and gasolene engines, and the invention has for its primary object the provision of novel means for automatically governing the explosions of an engine by the speed of the same.

15 My invention aims to provide positive and reliable means for effecting the perfect operation of an engine with a minimum of expenditure of fuel. To this end, I have devised a clutch-actuated mechanism in combination with a valve and ignition device for controlling the supply and consumption of fuel used in connection with the engine. Upon the basis of this combination, the application comprehends the embodiment of 20 the above combination for one specific purpose, namely the cessation of explosions after the engine has reached a predetermined speed, and a resumption of the explosions upon the engine having attained its 25 normal condition or speed.

30 My invention further aims to provide a novel engine frame or casing for protecting the working mechanism of the engine and permitting easy access thereto.

35 With the above and other objects in view, the invention consists in the novel construction, combination and arrangement of parts to be hereinafter more fully described and then specifically pointed out in the appended 40 claims.

45 Referring to the drawing forming part of this application like numerals of reference designate corresponding parts throughout the several views, in which:

50 Figure 1 is a plan of my improved engine, a portion of the casing and the gasolene tank thereof being removed, Fig. 2 is an elevation of the engine, the gasolene tank being restored, Fig. 3 is a fragmentary horizontal sectional view of the engine, Fig. 4 is a fragmentary vertical sectional view of a portion of the engine, Fig. 5 is a longitudinal sectional view taken on the line $x-x$ of Fig.

3, Fig. 6 is a rear elevation of the engine, partly broken away, Fig. 7 is a detail sectional view of part of the clutch mechanism, Fig. 8 is an elevation of a spark igniter, Fig. 9 is a plan of the same, Fig. 10 is a detail sectional view enlarged of a portion of one of the gear wheels illustrating the arrangement 60 of the adjustable block carried thereby.

My improvement consists of a suitable foundation or bed plate 1 upon which is mounted the engine frame or casing, the frame comprises a standard 2 carrying a hollow casing 3 which terminates in an integral cylinder 4 having its outer or ignition end 5 surrounded by a water jacket 6, communicating with an integral water reservoir 7 extending upwardly from the cylinder 4. The 70 casing 3 is formed with bearings 8, and with an opening 9, whereby easy access may be had to the interior of the same. The casing 3 serves as a closure to the crank and the connecting rod leading to the piston of the 75 engine, the casing being closed by a lid or cover 11 hinged to the casing, as at 12 and connected to the casing at one side is a housing 10.

Journalized in the bearings 8 is a crank shaft 80 14 connecting with a rod 15, which is trunnioned in a piston head 16 that operates within the cylinder 4. Upon the ends of the shaft 14 are mounted wheels 17 and 18, one of said 85 wheels serving as a balance wheel, while the other wheel serves as a belt wheel.

Transversely of the housing 10 and parallel with the shaft 14 is journalized a shaft 19, upon which is mounted a flanged gear wheel 20 meshing with a gear wheel 21 keyed upon the 90 shaft 14, contiguous to the wheel 18. The flanged gear wheel 20 is provided with diametrically opposed lugs 22, and pivoted in said lugs are weighted bell crank levers 23, the ends of said levers engaging a clutch 95 member 24 slidably keyed upon the shaft 19. The weighted ends 25 of the bell crank levers 23 are arranged to be influenced by the centrifugal force exerted by the revolving gear wheel 20 and thereby adapted to actuate the 100 clutch member 24. In this manner the speed of my improved engine governs the movement of the clutch member 24 and the mechanism actuated by the same.

The housing 10 supports a pivoted lever 105 26 having a bifurcated end 27 embracing a

sleeve 24. Connecting with the end 27 of the lever 26 is a depending link 28, which is mounted in the end of a shaft 29, revolubly mounted in a boss 30, carried by the housing 5 10. The outer end of the shaft 29 is provided with a crank arm 31 through the lower end of which passes a rod 32, carried by the housing 10. Upon the rod 32 is mounted a spring 33 adapted, through the medium of the shaft 10 29, to maintain the sleeve 24 in close proximity to the gear wheel 20. The outer notched end of the lever 26 serves a function which will be presently described.

The water jacket 6 upon one side is enlarged, as at 34 to accommodate the gasoline exhaust and inlet elements of my improved engine. In the jacket 6 is formed a curved exhaust passage 35, communicating with the cylinder 5 by a port 36. The junction of the passage 35 and port 36 forms a valve seat 37 for a valve 38, said valve being carried by a rod 39 extending through a sleeve 40 formed in the jacket 6. The end of the rod 39 is connected by nuts 41 to a plate 25 42, slidably mounted through the housing 10. In the end of the plate 42 is journaled a roller 43 adapted to engage with an eccentric disk 44 fixed upon the shaft 19. Through the medium of the disk 44, plate 42 and rod 39, 30 the valve 38 is opened. Secured to the plate 42 is an arm 45 adapted to be engaged by the lever 26, said lever serving functionally as a detent to withhold the valve 38 from the seat 37.

35 Disposed upon the rod 39, between the nuts 41 and the jacket 6 is a coiled spring 46, adapted to close the valve 38. Mounted between the nuts 41 is an arm 47 carrying an insulated finger 48, adapted to contact with 40 an adjustable beveled block 49, carried by the gear wheel 20.

Formed in the water jacket 6 is a bore 50 communicating with the port 36. In the bore is mounted an inlet valve casing 51 having a spring held valve 52 alternately actuated with relation to the valve 38. Connecting with the valve casing 51 is a pipe 53, carrying a mixer 54 of a conventional form adapted to correctly proportion and thoroughly mix the charge of gasoline and air. The mixer 54 is connected by a pipe 55 to a gravity feed gasoline tank 56, carried above the water reservoir 7.

In the explosion end 5 of the cylinder 4 55 is mounted an electric igniter 57, through which an electric current passes from water proof dry batteries, located in a box 58 at one end of the engine. The electric current is controlled by a spark coil located in a water 60 proof case 59, and by a switch 60.

The wiring between the various parts of my engine is as follows: The batteries in the box 58 are connected to the engine frame or casing 3 by a wire 61, and to the switch

60 by a wire 62. The switch connects with the spark coil within the casing 59 by a wire 63, while another wire 64 connects said coil with the finger 48. The igniter 57 connects with the spark coil by a wire 65, and upon said wire is located a spark indicator 66. The indicator comprises two insulated plates 67 having a sight opening 68. Between the plates 67 are secured copper terminals 69, that connect with the wire 65. The electric current is adapted to jump from one terminal to another, whereby the sparking of the igniter can be indirectly observed. 75

In connection with my improved engine, I use a bearing 70 for the cylinder 4, a lubricator 71, and an exhaust muffler 72. 80

Operation. We will assume that a charge of mixed air and gasoline has been admitted to the explosion end 5 of the cylinder 4 through the port 36, and has been ignited to drive the piston 16 forward. The shaft 14 85 will be revolved through the medium of the piston rod 15, imparting a rotary movement to the shaft 19 and the gear wheel 20 mounted thereon. The impetus or centrifugal force of the gear wheel 20 will move the sleeve 24 90 inwardly towards the gear wheel 20, this being accomplished through the weighted bell crank levers 23. As the sleeve 24 is so moved, the lever 26 is moved to engage the arm 45 of the plate 42. The arm 45 is 95 moved outwardly by the eccentric disk 44 engaging the roller 43 of the arm 42, the outward movement of the plate 42 being previous to the movement of the lever 26, whereby when the plate 42 is about to return 100 to its normal position, the end of the lever 26 will retard the movement of said plate. By holding the plate 42, the exhaust valve 38 is held in an open position and thus allowing the cylinder 4 to exhaust. Simultaneous 105

with the movement of the elements just described, the electric circuit which passes through the igniter 57 is broken and remains broken until the next injection of mixed gasoline and air into the cylinder of the engine. The first explosion within the cylinder 4 of the engine gives the engine sufficient impetus to operate for a short period of time, and in order that the speed at which the engine is operated may govern the detonations 115 of the engine, I employ the adjustable block 49, the arm 47 and the finger 48, the bell crank levers 23 carried by the gear wheel 20 being weighted, so that the sleeve 24 will assume its normal position when the revolutions of the engine have reached a predetermined speed. As the engine "runs down" the sleeve 24 returns to its normal position, moving the lever 26 and allowing the plate 42 and arm 45 to return to their 120 normal positions. This is accomplished by the spring 46. As the plate 42 returns to its normal position, the finger 48 is moved in

close proximity to the flanged gear wheel 20, and in the path of the adjustable block 49. As the block 49 contacts with the finger 48, a circuit is completed through the batteries, 5 sparking coil and igniter previously described. Simultaneous with the moving of the finger 48, the exhaust valve 38 is closed and the movement of this valve together with the piston 16, creates a suction which 10 opens the inlet valve 52, thus allowing the charge of mixed gasolene and air to enter the cylinder 4. The return movement of the piston 16 compresses the charge, and the completing of the electric circuit by the finger 15 48 causes the igniter to fire the gasolene and air. I have made the block 49 adjustable, whereby the detonations within the cylinder 4 may be regulated, either early or late, with relation to the charge of gasolene and air 20 admitted to the cylinder.

From the foregoing description it will be observed that I have devised an engine wherein a maximum amount of power may be derived from a minimum expenditure of fuel, 25 also a saving in the wearing parts of the cylinder, owing to the fact that the explosions cease when the engine has reached a pre-determined speed.

I do not care to confine myself to the type 30 of engine in connection with which the explosion regulating mechanism is employed, as this feature of my invention is applicable to various types of engines wherein ignition devices are used.

35 What I claim and desire to secure by Letters Patent, is:—

1. In a gas and gasolene engine, the combination with a casing, a cylinder carried by said casing and having an exhaust port formed therein, an electric igniter carried by 40 said cylinder, a revolute shaft mounted in said casing and actuated from said cylinder, of a housing carried by said casing, a shaft mounted in said housing, a gear wheel carried by said shaft and revolved by said casing shaft, a sleeve slidably mounted upon said shaft and actuated by said gear wheel, a plate slidably mounted in said housing and actuated in one direction to open said port, 45 means to move said plate in the opposite direction, means to lock said plate in a fixed position, a finger carried by said plate and in circuit with said igniter and a suitable source of electrical energy, and adjustable means 50 carried by said gear wheel to make and break the circuit of said igniter.

2. In an explosive engine, the combination with a cylinder having an ignition device, said cylinder having an exhaust port formed 55 therein, and a valve controlling said port, of a shaft revolved through the medium of the piston in said cylinder, a gear wheel carried by said shaft and in circuit with said ignition device and a suitable source of electrical en-

ergy, a plate slidably mounted adjacent to 65 said gear wheel and connecting with the stem of said exhaust port controlling valve, an arm carried by said plate and a finger carried by said arm, a block on said gear wheel adapted to contact with said finger upon 70 each revolution of the said gear wheel to complete a circuit through said igniter, means carried by said shaft to move said plate, and means actuated by the centrifugal force of said gear wheel to temporarily hold 75 said plate.

3. In an explosive engine, the combination with a casing, a water cooled cylinder carried by said casing, and having an ignition device, said cylinder having a gasolene and 80 air inlet and exhaust port formed therein, and a drive shaft journaled in said casing, of a housing carried by said casing, a lid hinged to said casing and adapted to fit upon said casing and said housing, a shaft journaled in 85 said housing, a flanged gear wheel mounted upon said shaft and revolved by the drive shaft, said gear wheel being in circuit with said ignition device and with a suitable source of electrical energy, a sleeve slidably 90 mounted upon said shaft and actuated by the centrifugal force of said gear wheel, a pivoted lever carried by said housing and actuated by said sleeve, a plate slidably mounted in said housing and actuated by 95 the shaft of said housing, an arm carried by the plate and a finger carried by the arm, a block on said gear wheel adapted to contact with said finger upon each revolution of the gear wheel to complete a circuit through said 100 igniter, means carried by the said shaft to move said plate, and means actuated by the centrifugal force of the gear wheel to temporarily hold said plate.

4. In a gasolene engine, the combination 105 with an explosion-driven shaft in circuit with an igniter and a suitable source of electrical energy, of a wheel driven by said shaft, an adjustable block carried by said wheel, means contacting with said block to complete a circuit through said igniter, means actuated by said wheel to reciprocate the first mentioned means, and means actuated by said wheel to temporarily hold the first mentioned means.

5. In an explosive engine, the combination with a cylinder having a port formed therein, and having an igniter, a valve controlling said port, and a revolute gear driven through the medium of the piston in said cylinder and 120 in circuit with said igniter and with a suitable source of electrical energy, of means actuated by said gear to open said valve comprising a slidably mounted plate connected to the stem of said valve, a shaft on which said gear is mounted, and a cam carried by the shaft to engage said plate, means actuated by the centrifugal force of said wheel to automat-

ically lock said valve in an open position, said means comprising a pivoted lever, a sleeve on the shaft engaging one end of the lever, and a pin on the slideable plate to engage the other end thereof, and means to close said valve when the pivoted lever is moved out of engagement with said pin.

In testimony whereof I affix my signature in the presence of two witnesses.

ANTHONY FRICKER.
